UNITED STATES PATENT OFFICE.

CHARLES GORDON HODGE, OF PHILADELPHIA, PENNSYLVANIA.

DESIGN FOR AN ADVERTISING-CARD.

SPECIFICATION forming part of Design No. 29,642, dated November 8, 1898.

Application filed October 8, 1898. Serial No. 693,042. Term of patent 7 years.

To all whom it may concern:

Be it known that I, CHARLES GORDON HODGE, a citizen of the United States, residing at Philadelphia, in the county of Philadelphia and State of Pennsylvania, have invented a new and original Design for Advertising-Cards; and I do hereby declare the following to be a full, clear, and exact description of the invention, such as will enable others skilled in the art to which it appertains to make and use the same.

My invention relates to a new and original design for advertising-cards; and the object of my invention is the provision of an artistic, yet a very useful, device for this purpose.

In the accompanying drawings, Figure 1 represents a top plan view of my invention, and Fig. 2 is a sectional view thereof taken 20 through center of dial.

In the drawings I show a rectangular base A, having the circle B, whose periphery is divided into three hundred and sixty-five equal parts by means of the short and long straight lines, printed or otherwise formed upon the 25 surface thereof. Mounted upon this base and having its center coinciding with the center of the circle B is the dial or circle C, having a

space D between its periphery and the circle-inscribing line E, divided into three hundred and sixty-five equal parts by the straight lines, as shown, to correspond to the parts upon the outside circle B. Between the line E and another circle-inscribing line F is a space G, which is divided into the twelve 35 arched blocks or spaces H for the reception of the names of the months of the year, said spaces being arranged in sizes according to the number of days in each respective month. Around the edge or near the circumference 40 of the inner field or space I is the convoluted line J, which represents a stem or branch for the leaves K, and in the space between the ends of the line J is a picture of a dog's head L to ornament my design.

Having described and shown my invention, what I claim as new, and desire to secure by Letters Patent, is—

The design for an advertising-card, as herein shown and described.

In testimony whereof I affix my signature in presence of two witnesses.

CHAS. GORDON HODGE.
